HYDRAULIC LIFT ACTUATING MECHANISM

Filed Aug. 7, 1939

UNITED STATES PATENT OFFICE

2,250,803

HYDRAULIC LIFT ACTUATING MECHANISM

Frank Koenigkramer and Frederick Koenig-
kramer, Cincinnati, Ohio

Application August 7, 1939, Serial No. 288,730

8 Claims. (Cl. 155—26)

The present invention relates to an hydraulic lift actuating mechanism of the kind generally associated with barber's and beauticians' chairs, physicians' chairs and treatment tables, hospital litters and similar equipment having a seat or table portion to be tilted and locked in various inclined positions.

An object of the invention is to provide a lift for devices of the character referred to, with actuating and control means of an improved construction such as will facilitate the operation of the locking means for the seat and table elements of such equipment.

Another object of the invention is to simplify and reduce the number of levers and adjustment devices in equipment of the character mentioned, thereby to reduce manufacturing and maintenance costs while at the same time enhancing the safety and dependability of such equipment.

Another object of the invention is to unify to an extent heretofore unknown, the various adjustments and movements in control equipment for devices of the kind mentioned, thereby to accomplish the foregoing objects.

These and other objects are attained by the means described herein and disclosed in the accompanying drawing, in which:

Fig. 1 is an elevational view of an hydraulic lift for chairs, tables and the like, including the improved actuating and control mechanism of the invention.

Fig. 2 is a fragmental plan view looking down on the device of Fig. 1.

Fig. 3 is a fragmental elevational view of the operating handle details, showing the relationship of the parts when operative to release a tilt bar.

Fig. 4 is a plan view of a yoke which forms a detail of the invention, same being illustrated on a greatly reduced scale.

Fig. 5 is a side view of one form of lift-equipped chair having a tilting seat, to which the device of the present invention is applicable.

By way of introduction, reference may be had to the general view of Fig. 5 wherein 7 indicates a frame tiltable about a pivot 8 supported by the head box or casing 9 of a hydraulic lift mechanism. The lift mechanism ordinarily will consist of a pair of telescopic members 10 and 12 having a mounting frame 13 secured to a suitable base 14. Although the frame 7 in this view is shown as a chair frame, it might alternatively be the frame of a table as suggested hereinbefore. Devices of the general character disclosed in Fig. 5 are well known, and as will be readily under-

stood, the frame 7 may be lifted and lowered by manipulating an operating lever 19 through an arc in the upright plane which is substantially parallel to the longitudinal axis of the frame.

In accordance with the present invention, the operating lever has also a movement in a plane transversely of the frame axis, for the purpose of clamping and releasing a tilt rod or bar 15 which has a forward end 16 pivoted to a link 17, which link in turn is pivoted at 18 to the frame. When the frame is tilted about the pivotal point 8, the tilt rod or bar 15 will be shifted forwardly, that is to the right, upon proper release thereof by the operating lever in a manner to be hereafter explained. By clamping the tilt rod in various shifted positions, the inclination of the frame 7 will be definitely established, until such time as the tilt rod is released for return to the normally inoperative position of Fig. 5. In Figs. 1 and 2, the tilt rod or bar is indicated at 15.

Referring to Figs. 1 and 2, it will be observed that the head box or casing 9 is furnished with a bearing 20, which if desired, may extend a substantial distance from the wall 21 of the box 25 or casing, and said bearing is adapted to rotatably receive therein an actuating shaft 22 which is rotatable, but not reciprocable, within the bearing. One of the functions of rotation of said shaft is that of operating a plunger rod 23 which serves to elevate and lower the lift post 10. It is immaterial to the present invention whether the hydraulic lift mechanism be of one form or another, however, by way of explanation it may be assumed that the shaft 22 carries a crank 24 and a crank pin 25 connected with the plunger rod in such manner that rocking of the shaft 22 will properly actuate the hydraulic lift. The hydraulic lift may be of any acceptable type, for example, as disclosed in the Kochs et al. Patent No. 1,887,647, dated November 15, 1932.

As was previously stated, the operating lever 19 may be used not only for the purpose of rocking the shaft 22, but also for clamping and releasing the longitudinal shiftable tilt rod or bar 15. To so clamp and release the tilt rod the operating lever 19 is so constructed as to be shiftable about a pivot 26, in a direction lengthwise of the axis of shaft 22. The arrangement is such that such movement of the lever about pivot 26 will be effective for clamping and releasing the tilt rod, regardless of the inclination of said lever as determined by the operating shaft 22. In other words, the operating lever 19 as disclosed in Fig. 5 may be in the substan-

tionally vertical position there illustrated, or it may be in positions to the right or left of the indicated position, without in any way affecting the capability of the lever to clamp or release the tilt rod without rotation of the shaft 22.

The means whereby the foregoing functions are accomplished will now be described in detail. The head box or casing 9 will be seen to include the opposed walls 27 and 28 through which extends the tilt rod or bar 15. Suitable apertures or bearings 29 may be formed in said opposed walls to permit free longitudinal reciprocation of the rod 15. Closely adjacent, and parallel to the rod 15, a pivot rod or shaft 30 may be provided, the ends 31 and 32 of which provide studs for the pivotal mounting of the spaced arms 33 and 34 of a clamping yoke indicated generally by the character 35 (see Fig. 4). The yoke is adapted to be moved about its pivots 31 and 32 only slightly, but it will be seen that the journals 36 and 37 thereof through which the tilt bar or rod passes, will bear tightly against the rod or bar with a shearing force when the yoke is rotated about its pivotal mountings.

As is most clearly shown in Fig. 1, the free end of the yoke carries a cam follower 38, which may be in the form of a roller rotatably supported upon a shaft 39 passing through perforate ears 40 of the yoke. A cam which may be in the form of a cone 41, is adapted to be moved longitudinally of the shaft 22 for striking the follower 38 and forcing it downwardly for the purpose of moving the yoke about its pivotal mountings 31 and 32. Upon backing the cam or cone 41 from the follower or roller 38, the yoke will be elevated or returned to the operative or clamping position, under the influence of one or more compression springs 42. In the embodiment illustrated, the springs are conveniently seated upon a ledge or flange 43 of the head box or casing, and if desired the springs may be rendered adjustable as to their compression forces by interposing an adjustable spring seat 44 between the web 45 of the yoke, and the stationary seat 43. A set screw or other suitable adjusting means 46 may apply the necessary force to the adjustable spring seat 44, by threading the screw through the web at the location 47.

From the foregoing, it should be readily apparent that movement of the cam or cone 41 to the left of Fig. 1 will result in lowering the free end of the yoke, thereby to compress the springs 42 as the yoke moves about its pivots 31 and 32, but incidental to such movement of the yoke, the tilt rod or bar 15 will be loosened in the journals 36 and 37 for shifting movement through the head box 9. Upon retraction of the cam or cone 41, that is, upon movement thereof to the right in Fig. 1, the follower 38 will be relieved of the force applied thereto by the cam or cone, whereupon the springs 42 will return the yoke to the elevated position at which the clamping action thereof upon the tilt rod or bar will be reestablished.

By referring to Figs. 1 and 2, it will be seen that a suitable compression spring 48 encircling the shaft 22 with its ends abutting the bearing 20 and the cam or cone 41, serves always to move the cam or cone to the right, at which position of the latter, the springs 42 exert the necessary force for effecting the clamping action between the yoke arms and the tilt rod 15.

The means for shifting the cam or cone 41 longitudinally of shaft 22 includes the same lever 19 that is employed in operating mechanism for elevating and lowering the lift. Said means may

comprise a sleeve 49 which is shiftable with the element 41 along the shaft 22, said sleeve having its end 50 in abutment upon the element 41. Either integrally with or separate from the sleeve 51 is an abutment plate 51 which, if desired, may be in the form of a disc. The plate 51 is adapted to be moved to the left, together with sleeve 49 and cone 41, by the movement of lever 19 in a clockwise direction about its pivot 26, as indicated in the Fig. 3 illustration. It will be noted that the pivot 26 for lever 19 is supported in a block 52 which is fixed securely to shaft 22 at its outer end, so that rotation of the lever to the Fig. 3 position will place the cam face 53 of the lever in forceful contact upon the abutment plate 51, and by reason of the fact that the shaft 22 is not shiftable lengthwise, due to the integral shoulder 70 abutting the casing wall 21, the abutment plate necessarily will shift to the left for forcing the cam or cone 41 against the follower 38 of the yoke, thereby to lower the free end of said yoke as heretofore explained, to release the clamping force upon the tilt rod or bar 15. If desired, the block 52 may carry an extending pin or guide member 54 arranged in substantial parallelism with shaft 22, which pin or guide member may project through a perforation or slot 55 formed in the abutment plate 51, thereby providing for rotational movement of the abutment plate with the shaft 22 when lever 19 is manipulated for rocking the shaft and operating the lift mechanism.

Because of the probability that the lever 19 will in some instances assume a position quite close to the seat or table frame 7, it is desirable that means be provided for precluding rotation of the operating lever 19 about its pivot 26 in the counterclockwise direction, since such movement of the lever would probably result in interference by the frame 7. Accordingly, a stop 56 is bolted or otherwise fixed to the lever at a proper elevation such that the lower face 57 thereof will bear upon the periphery of abutment plate 51 upon attempted rotation of the lever to the left, from the position illustrated by Fig. 1. It will be observed by referring to Fig. 1, that the pivoted end of the lever preferably is bifurcated so as to furnish the spaced parallel arms 58 and 59 which embrace the pivot block 52. The fixation of block 52 to the end of shaft 22 may be effected in any proper manner, such as by means of a drive fit, a suitable key, or a spline connection, all of which is immaterial to the invention.

In conclusion it may be mentioned that spring 48 is merely auxiliary to springs 42-42, and may be omitted if springs 42-42 be made sufficiently forceful to shift the cam or cone 41 to the neutral or normal position of Fig. 1. The inclination of the face of cam or cone 41 may be increased, if necessary, to enable omission of spring 48 as suggested. In constructions wherein it may be considered necessary or desirable to have the tilt rod 15 at a higher elevation than the yoke arm, the clamping action may be effected at a notch or depression 60 formed in each yoke arm.

The construction described and disclosed herein is found to furnish a very convenient and simple means, all incorporated in a single operating lever control, for adjusting the height and also the degree of tilt of a frame such as 7, or of any other type of frame requiring the movements specified. The construction avoids the need for a multiplicity of levers or controls, thereby adding to the convenience and the understandability of operation, as well as to the appearance of the equipment. Additional advantages are stated in the

objects at the head of this description, and various minor advantages will be readily apparent to those skilled in the art.

It is to be understood that various modifications and changes may be made in the structural details of the device, within the scope of the appended claims, without departing from the spirit of the invention.

What is claimed is:

1. In a device of the class described, the combination of a lift to be selectively elevated and lowered, and a weight-supporting frame tiltably supported upon the lift, said lift including a head having opposed walls and a shaft bearing extending parallel to said walls, an operating shaft for the lift supported in said bearing rotatably and including means preventing longitudinal shifting of said shaft, a lever supported upon said shaft for rocking same, transverse pivot means connecting the shaft and lever for movement of the lever arcuately in a plane which passes through the shaft axis, a clamping yoke having arms pivoted upon the opposed walls of the lift head, and means for moving the pivoted yoke upon manipulation of the lever arcuately as stated, a tilt rod passing through the opposed walls of the lift head near the pivoted portions of the yoke, bearings in the yoke arms close to the pivot portions, said bearings slidably receiving the tilt rod upon movement of the lever in one direction about the transverse pivot means for the lever, and clamping the tilt rod upon movement of the lever in the opposite direction about said transverse pivot means, means connecting one end of the tilt rod to the tiltable frame whereby the rod in the clamping position of the yoke maintains the frame at various degrees of inclination, and means operative upon rocking the operating shaft for actuating mechanism to operate the lift.

2. In a device of the class described, the combination of a lift to be selectively elevated and lowered, and a weight-supporting frame tiltably supported upon the lift, said lift including a head having opposed pivots, a yoke including a pair of spaced arms each mounted upon a pivot of the head whereby the yoke may be rocked about said pivots, an extension on the yoke and a cam follower on the extension, a tilt rod connected to the tiltable frame and supported for sliding reciprocatory movement relative to the lift head, in substantial parallelism with the yoke pivots and closely adjacent thereto, means on the yoke arms for applying a force transversely to the tilt rod in one direction of rocking of the yoke, for clamping the tilt rod in longitudinally adjusted positions, an operating shaft extending from the lift head, and means responsive to rocking of said shaft for actuating mechanism to operate the lift, a lever for rocking the operating shaft, a cam slidable upon the shaft for movement toward and from the follower of the yoke, for rocking the yoke to clamp and release the lift rod, and means associated with the lever for sliding said cam.

3. In a device of the class described, the combination of a lift to be selectively elevated and lowered, and a weight-supporting frame tiltably supported upon the lift, said lift including a head having opposed pivots, a yoke including a pair of spaced arms each mounted upon a pivot of the head whereby the yoke may be rocked about said pivots, an extension on the yoke and a cam follower on the extension, a tilt rod connected to the tiltable frame and supported for sliding reciprocatory movement relative to the lift head, in substantial parallelism with the yoke pivots and

5 closely adjacent thereto, means on the yoke arms for applying a force transversely to the tilt rod in one direction of rocking of the yoke, for clamping the tilt rod in longitudinally adjusted positions, an operating shaft extending from the lift head, and means responsive to rocking of said shaft for actuating mechanism to operate the lift, a lever for rocking the operating shaft, pivot means mounting said lever upon the shaft for movement arcuately in a plane which passes through the shaft axis, a cam slidable upon the shaft for movement toward and from the follower of the yoke, for rocking the yoke to alternatively clamp and release the lift rod, a cam face on the lever and a movable abutment plate on the shaft in position to be advanced by contact with the cam face of the lever when the latter is moved about its pivot means in the plane which is in the shaft axis, means transmitting movement of the abutment plate to the cam, and yielding means constantly urging the cam away from the follower of the yoke and for normally maintaining the clamping relationship between the yoke arms and the tilt rod.

10 4. In a device of the class described, the combination of a lift to be selectively elevated and lowered, and a weight-supporting frame tiltably supported upon the lift, said lift including a head having opposed pivots, a yoke including a pair of spaced arms each mounted upon a pivot of the head whereby the yoke may be rocked about said pivots, an extension on the yoke and a cam follower on the extension, a tilt rod connected to the tiltable frame and supported for sliding reciprocatory movement relative to the lift head, in substantial parallelism with the yoke pivots and closely adjacent thereto, means on the yoke arms for applying a force transversely to the tilt rod in one direction of rocking of the yoke, for clamping the tilt rod in longitudinally adjusted positions, an operating shaft extending from the lift head, and means responsive to rocking of said shaft for actuating mechanism to operate the lift, a lever for rocking the operating shaft, a cam slidable upon the shaft for movement toward and from the follower of the yoke, for rocking the yoke to release and clamp the tilt rod, means associated with the lever for sliding said cam in one direction along the shaft, and spring means for constantly urging the cam in the opposite direction along the shaft and for simultaneously maintaining the clamping relationship between the yoke arms and the tilt rod.

15 5. In a device of the class described, the combination of a lift to be selectively elevated and lowered, and a weight-supporting frame tiltably supported upon the lift, an operating shaft and an operating lever rockable in unison with said lever extending beyond the limit of a side of the frame, and including means for actuating mechanism to operate the lift, a connection between the shaft and the lever for pivoting said lever upon the shaft for arcuate swinging movement substantially at right angles to the direction of rocking movement aforesaid, a head on the lift having opposed pivots, a yoke including a pair of arms spaced apart to embrace the exterior of the lift head, said arms being mounted upon said opposed pivots of the head whereby the yoke may be rocked about said pivots, an extension on the yoke and a cam follower on the extension, a tilt rod connected to the tiltable frame and supported for sliding reciprocatory movement by and through the lift head, in substantial parallelism with the

20 30 35 40 45 50 55 60 65 70 75

yoke pivots and closely adjacent thereto, and means on the yoke arms for applying a force transversely to the tilt rod in one direction of rocking of the yoke, for clamping the tilt rod in longitudinally adjusted positions, and a cam shiftable along the operating shaft to a position of contact with the cam follower of the yoke extension upon swinging of the lever arcuately as stated, the cam moving the follower to rock the yoke about its pivots to release and clamp the tilt rod.

6. In a device of the class described, the combination of a lift to be selectively elevated and lowered, and a weight-supporting frame tiltably supported upon the lift, said lift including an apertured head wherein the apertures are opposed and aligned substantially horizontally, a yoke including a pair of spaced integral arms extending about and exteriorly of the head, and pivot means horizontally disposed for rockingly supporting the yoke upon the head, a fixed extension on the yoke projecting laterally of the head, a tilt rod connected to the frame and extended through the aligned head apertures for reciprocatory movement in substantial parallelism with the yoke pivot means and closely adjacent thereto, whereby rocking of the yoke brings its arm into clamping contact upon the tilt rod, yielding means acting upon the yoke for normally maintaining the clamping contact aforesaid, an operating lever and a shaft therefor mounted upon the lift, means pivotally supporting the lever upon the shaft for arcuate movement in a plane which substantially includes the shaft axis, and means operated upon movement of the lever as stated, for engaging the yoke extension and displacing the yoke from clamping position in opposition to the force of the yielding means aforesaid.

7. In a device of the class described, the combination of a lift including a transversely apertured head to be selectively elevated and lowered, and a weight-supporting frame including a pivot tiltably supporting the frame upon the lift, means for actuating the lift including a shaft rockable in substantial parallelism with the supporting pivot of the frame, and a lever for rocking said shaft, a connection between the shaft and the lever for pivoting said lever upon the shaft for arcuate swinging movement substantially at right angles to the direction of rocking movement aforesaid, means normally holding the frame against tilting relative to the lift, said means including a tilt rod having an end connected to the

tilting frame and an opposite end portion received in the transverse aperture of the lift head, an arm pivoted to the lift head for movement in close parallelism to the head and transversely 5 against the opposite end portion of the tilt rod, thereby to apply a shearing force to said rod, resilient means for normally yieldingly maintaining the shearing force of the arm against the tilt rod as said rod rests within the aperture of the lift head, and a release means for displacing the arm from the shearing position, in opposition to the force of the resilient means, operative upon swinging the lever arcuately at substantially a right angle to the direction of rocking movement 10 of the operating shaft.

8. In a device of the class described, the combination of a lift including a transversely apertured head to be selectively elevated and lowered, and a weight-supporting frame including a pivot 20 tiltably supporting the frame upon the lift, means for actuating the lift, including an operating shaft rockable in substantial parallelism with the supporting pivot of the frame and an operating lever for rocking said shaft, a connection between the shaft and the operating lever for pivoting said lever upon the shaft for arcuate swinging movement substantially at right angles to the direction of rocking movement aforesaid, a clamping device normally clamping the frame against 25 the shaft and the operating lever for pivoting said lever upon the shaft for arcuate swinging movement substantially at right angles to the direction of rocking movement aforesaid, a clamping device normally clamping the frame against the shaft and the operating lever for pivoting said lever upon the shaft for arcuate swinging movement substantially at right angles to the direction of rocking movement aforesaid, a clamping device normally clamping the frame against 30 the shaft and the operating lever for pivoting said lever upon the shaft for arcuate swinging movement substantially at right angles to the direction of rocking movement aforesaid, a clamping device normally clamping the frame against the shaft and the operating lever for pivoting said lever upon the shaft for arcuate swinging movement substantially at right angles to the direction of rocking movement aforesaid, a clamping device normally clamping the frame against 35 the shaft and the operating lever for pivoting said lever upon the shaft for arcuate swinging movement substantially at right angles to the direction of rocking movement aforesaid, a clamping device normally clamping the frame against the shaft and the operating lever for pivoting said lever upon the shaft for arcuate swinging movement substantially at right angles to the direction of rocking movement aforesaid, a clamping device normally clamping the frame against 40 the shaft and the operating lever for pivoting said lever upon the shaft for arcuate swinging movement substantially at right angles to the direction of rocking movement aforesaid, a clamping device normally clamping the frame against the shaft and the operating lever for pivoting said lever upon the shaft for arcuate swinging movement substantially at right angles to the direction of rocking movement aforesaid, a clamping device normally clamping the frame against 45 the shaft and the operating lever for pivoting said lever upon the shaft for arcuate swinging movement substantially at right angles to the direction of rocking movement aforesaid, a clamping device normally clamping the frame against the shaft and the operating lever for pivoting said lever upon the shaft for arcuate swinging movement substantially at right angles to the direction of rocking movement aforesaid, a clamping device normally clamping the frame against 50 the shaft and the operating lever for pivoting said lever upon the shaft for arcuate swinging movement substantially at right angles to the direction of rocking movement of the operating shaft.
